UNITED STATES PATENT OFFICE.

GEORGE F. ARMSTRONG, OF HAMILTON, ONTARIO, CANADA.

HEATER FOR INCUBATORS.

1,130,052.

Specification of Letters Patent.

Patented Mar. 2, 1915.

Application filed February 27, 1914. Serial No. 821,421.

To all whom it may concern:

Be it known that I, GEORGE FRANCIS ARMSTRONG, a subject of the King of Great Britain, and a citizen of the Dominion of Canada, residing at 218 Aberdeen avenue, in the city of Hamilton, county of Wentworth, Province of Ontario, Dominion of Canada, have invented certain new and useful Improvements in Heaters for Incubators, of 10 which the following is a specification.

This invention relates to heaters for incubators and it has more particular reference to a device which is intended to serve as a substitute for the ordinary coal-oil heater 15 and the like.

The object of my invention is to provide a neat and compact heater which can be readily placed in position and at the same time is absolutely controllable in so far as 20 the degree of temperature is concerned.

With these objects in view my invention consists in the novel features of construction, arrangement and combinations of parts as hereinafter fully described and more particularly pointed out by the appended 25 claims.

The accompanying sheet of drawings is in illustration of one practical embodiment of my invention, Figure 1, being an elevation 30 of a heater constructed in accordance with my improvements. Fig. 2, is a top plan of the same.

According to the form of my invention illustrated 1, is a rectangular or other suitably shaped base of insulating material suitably mounted on feet or the like 2, 2.

3, 3, are rods or uprights suitably incased in insulating material and provided with spacing or lock-nuts 4, 4.

40 5, is an upper or cover plate of sheet steel or the like which is supported on the aforesaid rods 3, 3, as shown and it is provided with a central opening or aperture 6, for the egress of the warm air from the heater to 45 the incubator chamber.

7, 8, 9, 10, and 11, are binding screws passing through the base 1, and being adapted to have coupled thereto conducting wires, 12, 13, 14, 15, and 16, connecting with the 50 heating coils as hereafter explained.

17, 17, are the terminal screws or posts for the source of power such as an ordinary electric light cable connection.

19, 20, 21, 22, and 23, are ordinary switches for coupling up any one of the 55 heating coils 24, 25, 26, 27, and 28. These heating coils 24, 25, 26, 27 and 28, comprise sheets of mica adapted to fit neatly and be clamped in the spaces between the rods or uprights 3, 3, and plates 1, and 5; and they 60 are wound with resistance wire. The wire used may be of finer gage in some cases thereby giving different degrees of heat. The lower ends of the resistance wires 29, are connected to the binding screws 7, 8, 9, 65 10, and 11, and the upper ends thereof are suitably united to the top plate 5, in any of the well known ways. There are altogether—in the form of my invention shown—five heating coils, two 25, 26, on one 70 side of the heater, and one on each of the other three sides.

29 designates a binding band of insulating material which aids in keeping the parts in place. The sheets of mica 30, with their 75 windings 24, 25, 26, 27 and 28 are held in place by being bound between plate 5 and base 1, when nuts 4 are tightened, it being understood that the heating elements so formed constitute the sides of a hollow 80 square.

The operation of the invention will be self evident to those skilled in the art to which it appertains and I wish it clearly understood that I do not restrict myself to the precise 85 details above outlined but deem myself privileged to make such reasonable modifications as may fairly be construed as falling within the ambit of the appended claims.

Having thus described my invention what 90 I claim as new and desire to secure by Letters Patent, is:—

1. In a device of the character described, a heater for incubators comprising an insulating base plate, a cap plate and a plurality of sheets of mica wound with resistance wire and bound between said base plate and said cap plate to form a hollow square. 95

2. In a device of the character described, a heater for incubators comprising an insu- 100

lating base plate, a cap plate, and a plurality of sheets of mica wound with resistance wire and bound between said base plate and said cap plate to form a hollow square, there being five of said sheets of mica, one arranged upon each of three sides of the square and two upon the remaining side.

Copies of this patent may be obtained for five cents each, by addressing the "Commissioner of Patents, Washington, D. C."

Signed at Hamilton, county of Wentworth, Province of Ontario, Canada, this 9th day of February, A. D. 1914.

G. F. ARMSTRONG.

In the presence of—

ALFRED T. BRATTON,
GERTIE NICHOLSON.
